UNITED STATES PATENT OFFICE.

CLYDE S. ROBB, OF CHARLEROI, PENNSYLVANIA, ASSIGNOR OF ONE-HALF TO CHARLES J. KUNZLER, OF PITTSBURGH, PENNSYLVANIA.

MANUFACTURE OF GLASS CYLINDERS.

Application filed January 14, 1920. Serial No. 351,389.

To all whom it may concern:

Be it known that I, CLYDE S. ROBB, a citizen of the United States, residing at Charleroi, in the county of Washington and State of Pennsylvania, have invented certain new and useful Improvements in the Manufacture of Glass Cylinders, of which the following is a specification.

Referring to the drawing,

10 The figure is a sectional elevation of one form of glass drawing apparatus which may be used in carrying out the invention.

15 My invention has relation to the machine manufacture of window glass cylinders, and more particularly to the method and means for supplying air to the interior of the cylinder while it is being drawn. The object of the invention is to provide an air supply system of this character which will operate to very largely reduce the pulsation bumps of the cylinder.

20 The apparatus of this application is shown in my prior application Serial No. 142,622, filed January 16, 1917, on which 25 my Patent No. 1,256,260 was issued February 12, 1918, and also in my Patent No. 1,356,739, issued October 26, 1920.

25 In the accompanying drawing, I have illustrated my invention as applied to a type 30 of drawing apparatus in which the air for the cylinder is supplied upwardly through the bottom of the pot, but my invention is not limited to such system of air supply, but may be used in connection with other 35 arrangements thereof.

In these drawings, the numeral 2 designates a pot or receptacle of any usual or 40 preferred construction and which is mounted on the foundation 3 having therein the well 4 which communicates upwardly through the bottom of the pot by means of the opening 5. 6 is a nozzle block supported on the bottom of the pot from the opening 5, and which projects above the 45 level of the molten bath in the pot, and is designed to deliver air into the interior of the cylinder.

50 7 designates any suitable bait which is arranged to be lowered into the molten glass and then drawn upwardly. In the drawings, I have illustrated the same form of drawing apparatus as shown in my said Patent No. 1,256,260, but it will be under-

stood that the present invention is independent of any particular form of bait or drawing apparatus.

8 designates an air supply pipe which is shown as extending into the well 4 with a delivery portion 8^a arranged centrally within the opening 5, and to which pipe air 60 is supplied from any usual or suitable source.

65 In accordance with my invention, the delivery portion 8^a of the pipe 8 has an internal diameter, such that its cross sectional area is considerably smaller than the cross sectional area of the cylinder A, which is being drawn. The passage to the cylinder through the nozzle 6 beyond the end of the pipe member 8^a should have a larger cross 70 sectional area than the internal cross sectional area of said pipe member, but smaller than the cross sectional area of the cylinder. The cross sectional area of the opening 5, adjacent to the discharge end of the pipe 75 8^a should also be preferably less than the cross sectional area of the cylinder being drawn.

80 It has been found that the arrangement shown is an effective one, greatly reducing the pulsation bumps, the manner in which the delivery portion of the air supply pipe is arranged providing for an effective vent. As is well known in the drawing of window glass cylinders, it is essential to provide a vent of the air supply system for the purpose of reducing pulsations, such vent operating as an automatic regulator in a manner which is not thoroughly understood, but which is effective in practice. I am not at present fully advised as to the exact reasons which cause my improved arrangement of the air supply system to operate as a more efficient vent than has heretofore been provided, but it appears 90 to be due, in part at least, to the injector action of the air escaping from the pipe member 8^a, and which tends to draw air in from or through the well 4, while at the same time said well operates as an automatic 95 release for any excess pressure which may occur within the cylinder being drawn.

100 The advantages of my invention result from the material reduction of the pulsation bumps of the cylinders produced, where- 105 by cylinders of any practicable length may

be obtained, which, for commercial purposes, are sufficiently free from bumps to enable them to be readily flattened.

As above indicated, the type of air supply may be varied, the sizes of the pipes and openings may be varied, within the general requirements above stated, and the relative position of the parts may also be changed.

10 I claim:

1. In apparatus for drawing glass cylinders, a stationary conduit having a passage leading to the bottom portion of the article being drawn, an air supply pipe arranged to discharge thereinto, said conduit and its opening being in injector relation to the discharge end of the air supply pipe and providing clearance space for escape of excess air, substantially as described.
2. In apparatus for drawing glass cylinders, a stationary conduit having a passage leading to the bottom portion of the article being drawn, an air supply pipe arranged to discharge thereinto, said conduit and its opening being in injector relation to the discharge end of the air supply pipe and of less area than the cross sectional area of the article being drawn, substantially as described.
3. In apparatus for drawing glass cylinders, a stationary conduit having a passage leading to the bottom portion of the article being drawn, an air supply pipe arranged to

discharge thereinto, said conduit and its opening being in injector relation to the discharge end of the air supply pipe and of less area than the cross sectional area of the article being drawn, and the cross sectional area of the air supply pipe at its discharge end being less than the cross sectional area of said passage, substantially as described.

4. In the machine manufacture of glass cylinders, the method of supplying air to the interior of the cylinder being drawn, which consists in forcing a jet or stream of air under pressure from a conduit into and through a passage leading directly to the bottom of the cylinder and across a venting space thereof through which excess air returns directly in opposition to incoming air, substantially as described.

5. In apparatus for drawing glass cylinders, a batch containing vessel, a conduit extending upwardly therethrough opening directly within the formative zone of the article being drawn and in open communication with the atmosphere below, and an air supply pipe leading to but spaced away from said conduit to supply air upwardly through the conduit while allowing for return flow of excess air backwardly through said conduit and around said pipe.

In testimony whereof I hereunto set my signature.

CLYDE S. ROBB:
